(57) **CLAIM**

The ornamental design for a jet face, as shown and described.

DESCRIPTION

FIG. 1 is a perspective view of a jet face;

FIG. 2 is a front view thereof;

FIG. 3 is a side, sectioned view thereof; and,

FIG. 4 is a side view thereof.

The broken line showing of parts of the drawings is included for the purpose of illustrating use and environment and forms no part of the claimed design.

1 Claim, 4 Drawing Sheets

FIG. 1

FIG. 2

FIG. 3

FIG. 4
